CLAIM

The ornamental design for the adjustable gas tube, as shown and described.

DESCRIPTION

FIG. 1 is a front perspective view of an adjustable gas tube showing my new design;

FIG. 2 is a top plan view thereof;

FIG. 3 is a bottom plan view thereof;

FIG. 4 is a side elevational view thereof;

FIG. 5 is a front elevational view thereof;

FIG. 6 is a side elevational view of another embodiment thereof;

FIG. 7 is a front elevational view thereof;

FIG. 8 is a side elevational view of another embodiment thereof; and,

FIG. 9 is a front elevational view thereof.

FIG. 1.

FIG. 2.

FIG. 3.

FIG. 4.

FIG. 5.

FIG. 6.

FIG. 7.

FIG. 8.

FIG. 9.
